H. HANSON

BILGE PUMP

Filed Oct. 1, 1921

Inventor
Henry Hanson
By George H. Hays
Atty

UNITED STATES PATENT OFFICE.

HENRY HANSON, OF MIDDLETOWN, CONNECTICUT, ASSIGNOR TO WILCOX, CRITTENDEN AND COMPANY, INCORPORATED, OF MIDDLETOWN, CONNECTICUT, A CORPORATION OF CONNECTICUT.

BILGE PUMP.

Application filed October 1, 1921. Serial No. 504,585.

To all whom it may concern:

Be it known that I, HENRY HANSON, a citizen of the United States, residing at Middletown, in the county of Middlesex and

5 State of Connecticut, have invented certain new and useful Improvements in Bilge Pumps, of which the following is a specification, reference being had therein to the accompanying drawings.

10 This invention relates to new and useful improvements in bilge pumps.

It is the object of the invention, among other things, to provide a pump of this character that may be readily connected with and 15 disconnected from the propeller or other driving shaft, whereby the pump may be operated at will and from any part of the vessel, and to produce a self-contained mechanism that may be set up and taken 20 down as a unit.

Among other arrangements and objects of the invention may be recited the provision of a device of the character mentioned, with a view to compactness, in which the number of 25 parts are few, the construction simple, the cost of production small, and efficiency and operation high.

To these, and other ends, my invention consists in the bilge pump having certain details of construction and combinations of parts as will be hereinafter described and more particularly pointed out in the claims.

Referring to the drawings, wherein like reference characters designate like parts in 35 the several figures:

Figure 1 is a side elevation of my improved bilge pump with the propeller shaft in section and a driving gear thereon.

Figure 2 is a plan view thereof, the parts 40 in section being upon line 2—2 of Figure 1;

Figure 3 is a sectional elevation of the cylinder and the laterally projecting lug and ball valves, taken generally upon line 3—3 of Figure 2; and

45 Figure 4 is a transverse section of the shaft, taken generally upon line 4—4 of Figure 2.

Bilge pumps generally are continuously operated from the propeller shaft. It is not necessary and in fact is not desirable that

the bilge pump should operate during all of the time that the propeller shaft is rotating. Means have been provided, however, for disconnecting the bilge pumps from the propeller shaft but have generally been so designed 55 as to be more or less complicated in operation, impossible of operation under some conditions, frequently require the stopping of the propeller shaft, and always require the attention of the operator at the bilge 60 pump itself.

The bilge pumps as heretofore constructed have not been entirely self-contained, that is, the parts thereof so related to a single member as to constitute a unitary structure 65 and the valves and the inlet and outlet pipe connection with the cylinder have been members separate from the cylinder.

The above, and other objections, to the bilge pumps in the prior art I have overcome in my new and improved device.

In the drawings, 10 designates the base member, reinforced by the rib 44 and upon which are the standards 11—11 at one end and the standards 12—12 at the opposite end. 75 Secured to the top of the latter standards, by the screw 14 or similar means, is the cylinder 13 having one closed end, and adjacent thereto the radially projecting lugs 15 which are interiorly threaded at 16 with ball 80 valves 17 of conventional form connected therewith. The cylinder is drained of accumulated water therein, when desired, through an aperture in the underside of the rear end thereof, normally closed by the 85 plug 43.

A plunger 18 is movable within the cylinder and upon the outer end of which is threaded a nut 19 containing a gasket or packing, as may be most suitable.

90 Journalized within the standards 11 is a shaft 20 having thereon an eccentric collar 21, upon which is rotatably mounted the gear 22 and an eccentric collar 23. This gear and collar are secured together by one or more dowel pins 24 so that they operate as a unit. Other securing means may, of course, be substituted or the two parts made integral. A collar 25 upon the eccentric collar 21 prevents endwise movement of the gear 22 and 100

eccentric collar 23 thereon, and a pin 26 that passes therethrough, through the collar 21 and the shaft 20 provides convenient means for securing the eccentric collar 21, shaft 20 5 and the collar 25.

Encircling the eccentric collar 21 is the eccentric strap 27 which is split at 28, and by means of the screw 29 and nut 30 it may be held in proper frictional relation to said 10 collar. This strap has a hinged connection with the plunger 18 through the pin 31. A stop pin 32 that projects radially upon opposite sides of the shaft 20, contacts with a fixed stop 33 connected with one of the 15 standards 11 to limit the movement of the shaft about its axis.

Rotation is imparted to the shaft 20 through the gear sector 34, journaled at 35, and having an arm 36 connected therewith, 20 the teeth of which mesh into those on the sector 37 that is adjustably and frictionally secured to the shaft 20 by means of the screw 38 connected with the integral ears 39. Any one of many other convenient 25 means may be substituted for securing this sector, but it is desirable that it be so connected with the shaft as to be moved into various positions about the axis thereof, thereby accommodating the sector 34, which 30 may, by reason of the construction of the vessel to which the pump is connected, occupy a different angle to the base member 10 than that shown herein.

The propeller or other shaft from which 35 the source of power is obtained to operate the bilge pump is designated 40, and connected therewith is a gear 41.

In Figure 1 the pump is shown with the teeth of the gear 22 in mesh with those of 40 the gear 41, at which time the plunger 18 of the pump is reciprocating within the cylinder 13, and the stop pin 32 is in contact with the fixed stop 33 in substantially the position shown by full lines in Figure 4.

45 If it is desired to stop the bilge pump, the arm 36 is manipulated so as to rock the sector 34 upon its pivot mounting, thereby imparting rotation to the shaft 20 and all mechanisms connected therewith. This 50 movement of the shaft 20 causes the eccentric collar 21 to travel about the axis of the shaft, and by reason thereof, the position of the gear 22 and eccentric collar 23 is shifted sufficiently to disengage the teeth of 55 the gear 22 from those of the gear 41 and thus separate the pump from its source of power. The pump parts now come to their rest position, at which time the stop pin 32 is against the fixed stop 33 in substantially the position shown by the broken lines 60 in Figure 4.

The arm 36, the upper end of which is shown broken off, may be operated either by 65 grasping the same or from any other portion of the boat by connecting it with a rope

or in any other convenient manner well known in the art. The pump may thereby be set in motion or stopped from any part of the vessel. As all of the mechanisms are connected with the base member 10, the 70 pump is assembled as a unit and secured by means of bolts or screws passing through the openings 42 therein. The ball valves and connections being integral with the cylinder it is merely necessary to thread a 75 pipe in the end of each and the pump is ready for operation.

There are minor changes and alterations that may be made within my invention, aside from those herein suggested, and I would therefore have it understood that I do not limit myself to the exact construction herein shown and described, but claim all that falls fairly within the spirit and scope of the appended claims. 80

Having described my invention, what I claim as new and desire to secure by Letters Patent, is:—

1. In a device of the character described, a base member; a shaft mounted therein and having an eccentric thereon; a sector secured thereto; a second sector pivotally mounted upon a fixed part, the teeth of which mesh into those of the first sector; a pinion loosely mounted upon said eccentric portion and an eccentric collar also mounted thereon and having a positive connection with said pinion; and a power transmitting member connected with said eccentric collar. 90

2. In a device of the character described, 100 a base member having standards thereon; a shaft mounted in said standards; an eccentric collar fixed on said shaft between said standards; a sector fixed to said shaft; a second sector pivotally mounted upon a 105 fixed part, the teeth of which mesh into those of the first sector; a pinion rotatably mounted upon said eccentric collar; a second eccentric collar loosely mounted upon said eccentric collar and having a positive 110 connection with said pinion; and a pitman connected with said second eccentric collar whereby reciprocatory motion is imparted during the rotation of said pinion.

3. In a device of the character described, 115 a base member; a shaft mounted therein and having an eccentric thereon; a sector secured thereto; a second sector pivotally mounted upon a fixed part, the teeth of which mesh into those of the first sector; a pinion and collar loosely mounted upon said eccentric; and a power transmitting member connected with said collar. 120

4. In a device of the character described, 125 a base member; a shaft mounted therein and having an eccentric thereon; means for limiting the rotation of said shaft in both directions; a sector secured thereto; a second sector pivotally mounted upon a fixed part, the teeth of which mesh into those of the first 130

sector; a pinion and collar loosely mounted upon said eccentric; and a power transmitting member connected with said collar.

5. In a device of the character described, a base member; a shaft mounted therein and having an eccentric thereon; a sector adjustably secured thereto; a second sector pivotally mounted upon a fixed part, the teeth

of which mesh into those of the first sector; a pinion and collar loosely mounted upon 10 said eccentric; and a power transmitting member connected with said collar.

In testimony whereof, I have hereunto affixed my signature.

HENRY HANSON.
